MEANS FOR THERMOSTATICALLY CONTROLLING GAS FIRED HEATERS AND THE LIKE

Clifford R. Roberts, Brighton, Mich.

Application February 15, 1939, Serial No. 256,605

4 Claims. (Cl. 175—363)

My invention relates to a method and apparatus for thermostatically controlling gas fired heaters and the like, in which the usual alternating current line voltage is stepped up and then rectified into a pulsating direct current which is thereafter filtered into ripple-free direct current and applied to the windings of the valve operating solenoid coil, this coil performing the operation of controlling the action of the valve regulating the flow of gas to the heater or the like, and an important object of my invention is to provide a simple and efficient arrangement of this character which eliminates the objectionable hum and chatter which usually obtains where alternating current is applied to devices of this general character.

Other important objects and advantages of my invention will be apparent from the reading of the following description taken in connection with the drawing, wherein for purposes of illustration I have set forth a preferred embodiment of my invention.

In the drawing:

The single view is a schematic wiring diagram showing an arrangement in accordance with the present invention.

Referring in detail to the drawing, the numerals 1 and 2 designate the respective wires of an A. C. input line, the wire 1 being connected to the point 3 of the thermostat 4 which is electrically connected to the contact point 5. If by action of the bimetallic element this contact 5 is made to touch the contact point 6 which is connected by the wire 7 to the transformer primary coil terminal 8, the other input wire 2 being connected to the primary coil at the terminal 9, a complete electrical circuit is established and a high voltage is induced in the secondary S—1 and this voltage appears at the terminals 11 and 15. The terminal 11 is connected by the wire 12 to the terminal 13 of the electronic rectifier or vacuum tube 14. The terminal 13 is connected by the wire 13a, sealed in a glass tube, to the electrode 13b. The terminal 15 is connected by the wire 16 to the terminal 17, and the terminal 17 is connected by the wire 17a, sealed in a glass tube, to the electrode 17b, the terminal 18 being connected by the wire 19 to a common negative ground.

The secondary winding S—2 of the transformer consists of comparatively few turns of wire and, therefore, produces a relatively low voltage which appears at the terminals 20 and 21. A wire 22 connects the terminal 20 with the terminal 23 of the rectifier tube 14, and the

terminal 21 is connected by a wire 24 to the terminal 25 of the tube 14. A wire 26, sealed in a glass tube in the rectifier tube is connected between the terminal 25 and the terminal 27 and the wire 28, also sealed in a glass tube in the rectifier tube but insulated from the wire 26, is connected between the terminal 23 and the terminal 29. Within the vacuum tube 14 is a strip of metal or other suitable material to form a filament 30 which completes the circuit between the terminals 27 and 29, and the resultant flow of current heats the filament 30 to redness causing electrons to be driven off therefrom. These electrons appear to be negative and alter the internal resistance of the vacuum tube 14.

With respect to the secondary S—1 of the transformer, the electrodes 13b and 17b of the vacuum tube being connected to the secondary terminals 11 and 15 respectively of the transformer 10, the electrodes 13b and 17b are at opposite polarities at all times. In other words, if the electrode 13b is positive, the electrode 17b will be negative and vice versa.

In view of this electrical condition, it is evident that while the electrode 13b is positive, current will flow toward the hot filament 30 but no current can flow from the electrode 17b which is then at a negative polarity. The terminal 18 of the transformer 10 is then also negative to the electrode 13b but at a potential of about one-half of the original voltage, due to the fact that the terminal 18 subtends only at one-half of the total number of turns of the transformer secondary winding S—1. This situation exists during one-half of each cycle. In the second half of the alternating current cycle, the electrode 17b becomes positive and the electrode 13b becomes negative, so that current flows from the electrode 17b toward the hot filament, but the repellent action of the negative electrons emitted by the hot filament prevent any current flowing from the negatively charged electrode 13b, so that the electrode 17b supplies a positive voltage to the terminals 23 and 25, inclusive, with the terminal 18 remaining negative. This arrangement produces a pulsating direct current voltage at approximately one-half the total secondary voltage between the terminal 18, or any position along the wire 19, and either terminal 23 or 25, inclusive.

The wire 31 is connected to the terminal 23 and extends to and is connected to the terminal 32, another wire 33, connected with the wire 31, is connected to the terminal 34 of the condenser 35, and the terminal 36 of the condenser 35 is

connected to the common or negative wire 19 thereby placing the condenser 35 directly across the output of the rectifier 14 and furnishes the conventional filtering action by removing the pulsations or ripple from the output of the rectifier, thereby producing a practically ripple-free direct current voltage. To the terminal 34 is affixed a resistance unit 37 which is connected to the terminal 38 of the relay or magnetic switch coil 39. The terminal 40 is connected by the wire 41 to the negative wire 19, thereby completing the circuit through the coil 39.

The function of the resistance unit 37 is to regulate the amount of current flowing in the coil 39. In operation the relay which is electrically connected to the terminal 32 at one end and has contact points 43, 44, respectively, at the movable end thereof should not change contacts until the voltage from the rectifier has reached a predetermined value slightly less than maximum. Rectifiers which depend on a heated filament for operation have a gradually increasing current output characteristic of the heating period of the filament, which gradually increasing current is unsatisfactory for the operation of a solenoid valve. However, if the action of the relay armature 42 be adjusted by regulating the current in the coil 39 so that the armature will operate at a voltage only slightly less than the maximum output of the rectifier, the resultant sudden application of this voltage to the solenoid coil 49 produces a quick, jerking action on the valve 55, and makes it possible to use a lower voltage and current in the solenoid coil, with consequently less heating effect and waste of current. The snap action of the relay is definitely a factor in the efficient operation of the system as a whole. During the off period and until a certain predetermined voltage is attained, the contact points 43 and 45 are engaged or closed. The contact point 45 is connected by the wire 46 to the resistance unit 47, and the wire 48 connects the remaining side of the resistance unit 47 with the wire 19, thereby establishing a complete circuit through the resistance unit 47, which is normally, or during the off period included in the output circuit of the rectifier of equal or preferably higher value than that of the solenoid coil 49. This condition exists during the heating period of the rectifier filament. However, when nearly the maximum voltage as mentioned above is obtained, the relay coil 39 is sufficiently energized to attract the armature 42 and thereby separate the contacts 43 and 45, thereby removing the resistance 47 from the circuit and simultaneously closing contact points 44 and 50 connecting the solenoid 49 in the same relation in the circuit as priorly occupied by the resistance 47. The solenoid coil 49 then receives the ripple-free direct current that priorly passed through the resistance 47, the said resistance being now inactive.

The contact point 50 is connected by the wire 51 to the terminal 52 of the solenoid coil 49, and the remaining terminal 53 of the coil 49 is connected to a wire 19 which is connected to the center tap 18 of the secondary winding S-1 of the transformer 10, whereby a complete circuit through the solenoid coil 49 is established, whereby the armature or plunger 54 is drawn upwardly and the lifting valve head 55 is moved from its seat, so as to allow gas to pass through the valve body to the heater or burner until enough heat has been generated to cause the thermostatic element of the thermostat 4 to open

the contacts 5 and 6. When the contacts 5 and 6 open all circuits become dead, and the valve head is allowed to return to its seat by force of gravity, and the relay armature 42 returns to its original position by reason of the action of the spring 42a, thereby causing the contact points 44 and 50 to open and re-establish the engagement between the contact points 43 and 45. This condition obtains and is sustained until such time as the thermostat is actuated by a temperature below that for which it is set, when the cycle of operation described above is repeated automatically.

Although I have shown and described herein a preferred embodiment of my invention, it is to be definitely understood that I do not desire to limit the application of the invention thereto, and any change or changes may be made in the structure and arrangement of the parts, within the spirit of the invention and the scope of the subjoined claims.

Having described the invention, what is claimed as new is:

1. In combination, a source of alternating current, an electronic rectifier tube, an electromagnetic switch having a single pole double throw element, said electromagnetic switch having one end of its movable arm connected, by wire, to one terminal of the said rectifier tube, the opposite end, of said movable arm being provided with suitable contact points for alternately connecting and disconnecting a phantom load circuit and a bona fide load circuit to the direct current output of the said rectifier tube, the said phantom load circuit and the said bona fide load circuit not being connected to the said rectifier tube circuit simultaneously, the said movable arm being so constructed that simultaneous connection of two circuits is prevented, the said electromagnetic switch to become operative at a predetermined voltage whereby the movable arm is made to change from one position to another position under the magnetic influence of an operating winding, said winding being of high resistance and connected, by wire, across the output of said rectifier tube, the said movable arm, upon deenergization of said operating winding, is made to change from one position to another position by the influence of a spring attached thereto, the said spring action providing a means for disconnecting the bona fide load circuit and providing for connecting the phantom load circuit to the direct current output of the said rectifier tube, the returns of said circuits being connected, by wires, to the mid tap of a supply transformer whose opposite ends of a secondary winding are connected, by wires, to the two anodes of said electronic rectifier tube, the cathode element of said electronic rectifier being considered as output terminal.

2. In combination, a source of alternating current supply, a transformer, a thermionic rectifier tube, an electromagnetic relay switch, said electromagnetic switch to comprise a movable element operable in two positions, a resistance unit to supply an artificial loading effect in the electronic tube circuit, said load to be effective during the heating period of the said electronic rectifier tube filament, the said electromagnetic switch being provided with suitable contact points for disconnecting the said artificial load when a predetermined voltage is attained in the rectifier tube and, by magnetic influence of an operating winding, applying said voltage to a bona fide load circuit, the said contact points

being controlled electromagnetically from the direct current output of the said electronic rectifier tube, the said electronic rectifier tube having the full alternating current voltage applied to its anodes simultaneously with the filament voltage, the said direct current being filtered by a conventional condenser connected, by wire, across the output terminals of the said electronic rectifier tube.

3. In combination, a source of alternating current, a rectifier tube, a resistor for loading said rectifier tube circuit during the heating period of the said rectifier tube filament, a condenser for filtering the pulsating direct current output of the said rectifier tube, an electromagnetic switch having an operable winding connected, by wires, across the filtered direct current output of the said rectifier tube, said electromagnetic switch being supplied with a movable element having suitable contact points for making connection to specific circuits alternately and at no time simultaneously, the said movable element being magnetically operated and electrically connected to one output terminal of said rectifier tube, said contact points being so adjusted that the said resistor will be normally in series with the rectifier tube elements until a predetermined voltage value is attained by magnetic influence, said contact points being caused to separate so as to effect isolation, electrically, of the said resistor, the said magnetic influence, still in evidence, effecting the closing of a different set of contact points, these said contact points effecting the connection of a bona fide load circuit by application of the full voltage, of the filtered direct current, thereby obtaining an instantaneous action, the said movable element, being held in the normal or warming position by a spring,

which, upon de-energization of its operable winding, returns to said normal position by spring action, the said spring action effecting the disconnection of the bona fide load circuit, and in the same motion, effecting the connection of the loading resistor to the direct current circuit, the said instantaneous action being effective in the bona fide load circuit.

4. In combination, a source of alternating current, a transformer, a thermionic rectifier, a loading resistor, a single pole double throw switch electromagnetically operated from said thermionic rectifier's output, said electromagnetic switch supplying a means for disconnecting said loading resistor from the thermionic rectifier circuit, also supplying a means for connecting a bona fide useful circuit to said thermionic rectifier's output, said connection means being caused automatically by a predetermined voltage obtained from said thermionic rectifier, said thermionic rectifier having a condenser bridged across its terminals for conventional filtering of the pulsating direct current, said switch providing a means for disconnecting said bona fide load circuit and supplying a means for connecting said loading resistor circuit, de-energization of the circuit allowing said switch to be controlled by a spring, said spring providing for action opposite to the action caused by the direct current voltage, said switch providing for no simultaneous connection to the thermionic rectifier's output circuit of the loading resistor and the bona fide load circuit, the said bona fide load circuit being disconnected from the said output circuit during the heating period of the thermionic rectifier's cathode.
